CONVERTIBLE BED AND DAVENPORT

John Strathaus, San Fernando, Calif.

Application January 14, 1949, Serial No. 70,857

5 Claims. (Cl. 5—59)

1

This invention relates to an article of furniture which may be used either as a bed or as a sofa or davenport, and has as a general object the provision of a furniture piece of attractive appearance which may be quickly converted from a bed to a sofa of the type usually known as a davenport, or from a sofa to a bed.

Numerous types of convertible bed-sofas are now available, but they are usually primarily sofas, designed to conceal their alternative function as beds and inadequately adapted to be converted into beds possessed of qualities of comfort and convenience. For example, the seat of a sofa of conventional width—that is, a sofa that properly supports the back without extending uncomfortably under the knees—is slightly too narrow to be comfortable as a single bed. A sofa of such proportions may have its back hinged to be lowered to the plane of the seat, forming a three-quarter bed, but one upon which it is impossible to tuck sheets and blankets unless an extra mattress is provided. The arm-rests of a sofa are usually low, and when used as head pieces for a bed, they are not high enough to support a stack of pillows behind a person wishing to sit up in bed.

It is accordingly a further object of this invention to provide a sofa convertible into a bed of adequate width.

Another object of the invention is to provide a sofa convertible in a bed which may be made up in the ordinary way of tucking blankets and sheets under the edges of the mattress—in this invention, the seat of the sofa—instead of merely draping them over the mattress with a hope that they will not slide off.

Still another object of the invention is to provide a sofa having conventionally low arm-rests which may be converted into a bed having relatively high head and foot pieces.

Yet another object of the invention is to provide a bed having the width, comfort, and conveniences of a standard single bed, which may be quickly converted into an attractive davenport.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

2

Referring to the drawings:

Figure 1 is a perspective view of a convertible bed and davenport, embodying the principles of this invention, showing the article of furniture made up as a davenport.

Figure 2 is a perspective view from the same aspect as Figure 1, showing the article of furniture in a stage of conversion.

Figure 3 is a perspective view from the same aspects as Figures 1 and 2, showing the article of furniture made up as a bed.

Figure 4 is a vertical sectional view on an enlarged scale, taken on the line 4—4 of Figure 1, with the direction of view as indicated, showing the upholstery cushion of the davenport back in conventional position, and, in broken line, moved to a position permitting the davenport to be converted to a bed.

Figure 5 is a fragmentary detail from Figure 4, on a further enlarged scale, showing the method of attaching the back upholstery of the davenport to the back support.

Figure 6 is another fragmentary sectional detail on approximately the scale of Figure 5, and taken on the line 6—6 of Figure 4, with the direction of view as indicated, showing the means used to mount the back support of the davenport pivotally upon the arm-rests.

Figure 7 is a horizontal sectional view on the plane of section indicated by the line 7—7 of Figure 6, showing means for controlling the pivotal movement of the davenport back support.

Figure 8 is a vertical fragmentary sectional detail on a further enlarged scale, taken on the plane of section indicated by the line 8—8 of Figure 7, showing further details of the means controlling the pivotal movement of the davenport back support.

Having reference now to the details of the drawings, my improved convertible bed and davenport may comprise a main frame 11 supporting a seat mattress 12 and having arm-rests 13 at each end secured to the frame and forming part thereof. One or more of the arm-rests 13 may contain a compartment 14, closable by a door 15. The frame 11 and the seat mattress 12 may have the width of a standard single bed, and of course the length of the seat mattress 12 between the arm-rests 13 is of suitable length for a bed.

Each of the arm-rests 13 has pivotally mounted thereon, as shown in detail in Figures 4 to 8, a back support 17. The two back supports 17 are each substantially half the length of the seat mattress 12 so as to be adapted to be swung

into contiguous alignment as shown in Figure 1, and then to form a virtually continuous back support slightly overlapping each arm-rest 13 to provide concealment for the hereinafter described pivoting and controlling mechanism. The frontal faces 18 of the back supports 17 preferably slope forwardly toward their lower margins 19 to provide a comfortably inclined back for a davenport, and the back supports are preferably formed as hollow cabinets 20 open at the frontal faces 18.

An upholstery cushion 22 is pivotally secured to each of the back supports 17, extending normally downwardly over the frontal face 18 of the back support to substantial contiguity with the seat mattress 12 and forming a closure for the cabinet 20. The cushions 22 may be secured to the back supports 17 in any suitable manner permitting them to be swung upwardly, as shown in broken line in Figure 4, but preferably I employ a hinge connection, as shown in Figure 5, which permits the cushions 22 to be easily disengaged and removed from the back supports. Plates 23 are inserted in the upper panelling 24 of the back supports 17, and have slots 25 for receiving hooks 26 secured to the rearward sides of the cushions 22. The forward margins 27 of the plates 23, defining the slots 25, form adequate hinge bars from which the hooks 26 may be easily disconnected.

Each of the back supports 17 is pivotally secured by a bearing bracket 29 to a pivot post 30, as shown in Figure 6, the post 30 extending downwardly into the arm-rest 13 and there being mounted in a bearing bracket 31. A collar 32 on the post 30 provides a supporting bearing for the back support 17, separating the lower surface of the back support and the upper surface of the arm-rest 13 sufficiently to permit swinging the back support without friction on the arm-rest.

To limit the pivotal movement of the back supports 17 to movement between the aligned positions above described in which they form a sofa back, and positions in upward extension of the arm-rests 13, in which they form head and foot members for a bed, a plate 34 is secured to the lower surface of each back support and has an arcuate slot 35 describing an arc of substantially ninety degrees. A plate 36 secured to the upper surface of the arm-rest 13 serves to locate a post 37, the upper end of which is adapted to travel in the slot 35. The post 37, accordingly, stops further pivotal movement of the back support 17 whenever either end of the slot 35 comes into contact with it.

When my convertible bed and davenport is to be used as a davenport, the back supports 17 are swung into alignment above the rearward margin of the frame 11 and seat mattress 12, and the upholstery cushions 22 are allowed to hang naturally from the hinge bars 27, as shown in Figure 1. The cushions 22 then cover the cabinets 20 and extend downwardly to the seat mattress 12, and are projected forwardly by the inclined faces 18 of the back supports 17, so as to reduce the effective width of the seat mattress 12 to a width appropriate for a davenport seat. To convert the article of furniture to a bed, it is merely necessary to raise the cushions 22, as shown in Figure 2, so as to clear the arm-rests 13, and to swing the back supports 17 to the positions shown in Figure 3, in upward extension of the arm rests. The cushions 22 are then allowed to drop as closures to the cabinets 20.

In this position, the back supports 17 form adequate head and foot members for a bed, permitting pillows to be banked against either support in a manner comfortable to a person sitting up in bed. Blankets and sheets may be tucked between the seat mattress 13 and the frame 11, as with an ordinary bed, as the seat mattress does not overhang the frame. The cabinets 20 are as readily accessible as the cabinet 14, providing space for storing personal articles.

I claim:

1. In an article of furniture convertible to either a bed or a sofa, a frame, a seat mattress supported by said frame, end members rigid with said frame and spaced apart for the reception of said mattress extending lengthwise therebetween, the tops of said end members being higher than the upper surface of said mattress, a pair of back supports pivotally mounted at opposite ends of said frame and adjacent one side thereof and spaced vertically from said seat mattress by a distance at least as great as the difference in height between the tops of said end members and the upper surface of said mattress, said back member being adapted for pivotal movement optionally to aligned positions above said one side wherein said back supports form a virtually continuous back support for a sofa or over said end members to positions removed from above said mattress, and upholstery members supported by said back supports and adapted to extend therefrom to said seat mattress when said back supports are in said first-mentioned positions.

2. In an article of furniture convertible to either a bed or a sofa, a frame, arm-rests at opposite ends of said frame, extending thereabove, a pair of back supports, means pivotally supporting said back supports above the level of said arm-rests and adapted to permit said back supports to be swung into positions of upward extension of said arm-rests and alternatively into aligned positions above one side of said frame wherein said back supports form a virtually continuous back support extending lengthwise of said article between said arm-rests, and means movable with respect to said back supports for extending said virtually continuous back support downwardly substantially to said frame.

3. In an article of furniture convertible to either a bed or a sofa, a frame, arm-rests at opposite ends of said frame, extending thereabove, a pair of back supports, means pivotally supporting said back supports above the level of said arm-rests and adapted to permit said back supports to be swung into positions of upward extension of said arm-rests and alternatively into aligned positions above one side of said frame wherein said back supports form a virtually continuous back support extending lengthwise of said article between said arm-rests, means for limiting pivotal movement of said back supports to movement between said first-mentioned and said last-mentioned positions, and means movable with respect to said back supports for extending said virtually continuous back support downwardly substantially to said frame.

4. In an article of furniture convertible to either a bed or a sofa, a frame, a seat mattress supported by said frame, arm-rests at opposite ends of said frame, extending thereabove, a pair of back supports, means pivotally supporting said back supports above the level of said arm-rests and adapted to permit said back supports to be swung into positions of upward extension of said arm-rests and alternatively into aligned

positions above one side of said frame wherein said back supports form a virtually continuous back support extending lengthwise of said article between said arm-rests, and upholstery members respective to each of said back supports and extending downwardly therefrom substantially to said seat mattress when said back supports are in said aligned positions, and being pivotally connected to said back supports so as to be raisable above said arm-rests when said back supports are moved toward said arm-rests.

5. In an article of furniture convertible to either a bed or a sofa, a frame, a seat mattress supported by said frame and having substantially the width of a single bed mattress, arm-rests at opposite ends of said frame, extending thereabove, a pair of back supports, means pivotally supporting said back supports above the level of said arm-rests and adapted to permit said back supports to be swung into positions of upward extension of said arm-rests and alternatively into aligned positions above one side of said frame wherein said back supports form a

virtually continuous back support extending lengthwise of said article between said arm-rests, and upholstery members respective to each of said back supports and extending downwardly therefrom substantially to said seat mattress when said back supports are in said aligned positions and forwardly to reduce the effective width of said seat mattress to a width appropriate for a sofa seat, and being pivotally connected to said back supports so as to be raisable above said arm-rests when said back supports are moved toward said arm-rests.

JOHN STRATHAUS.
